APPARATUS FOR AIR FLOATATION SEPARA-
TION

Edwin M. Rusk, Seattle, Wash.

Application September 8, 1933, Serial No. 688,660

1 Claim. (Cl. 209—466)

My invention relates to the art of separating or classifying materials and more particularly to apparatus for air floatation separation.

Many machines have been created for the purpose of separating and classifying materials and many different methods have been used in creating those machines each adapted to a specific purpose. In my present machine I employ the floatation properties of air under pressure to provide the separating, stratifying or classifying of materials. While there may be many industrial uses for my equipment I prefer to describe my equipment as it would be constructed and used in the recovery of metals from sand or from finely crushed materials.

When used as a gold recovery machine, for example, a very finely divided air-stream is directed under a column of gold bearing sand, and the pressure is so regulated that the grains of sand are lifted or held in the state of suspension similar in character to quick sand except that there is no water or other liquid present.

The principal object of my present invention is to provide a separating device for dry particles of different specific gravity wherein that separation is accomplished by causing the lighter particles to rise to the surface and flow over one edge of the hopper while the heavier particles are collected in the bottom of the receptacle.

A further object of my invention is to provide a device which will cause the stratification of dry particles so that they may be separated one from another.

A further object of my present invention is to provide a separating device which will separate dry particles of different specific gravity as a substantially continuous operation.

Other and more specific objects will be apparent from the following description taken in connection with the accompanying drawings, wherein

Figure 1 is a perspective view showing a separating unit built after the teachings of my invention.

Figure 2 is an exploded perspective view of the hopper bottom or air distributing means.

Figure 3 is a longitudinal vertical section thru my machine.

Figure 4 is a cross sectional view along the line 4—4 of Figure 3.

Referring to the drawings, throughout which like reference characters indicate like parts, numerals 10 and 12 designate a plurality of hopper-like receptacles of which any suitable number may

be employed. These hoppers are provided with the rather high sides 14 and 16 and end walls of different height as probably best shown in Figure 3 in which the end from which the machine is fed as 18 is considerably higher than the discharge end 20. The bottom of each receptacle is provided with an air-distributing means. In this connection it is desired to point out that means must be provided which will insure a very finely divided air stream. One solution that has been found quite satisfactory is to use material such as billiard cloth and to form it as a cup as indicated at 22. This can best be put in place by having its downwardly extending edges as 24 encircle an air distributing cone 26. Then the whole unit can be snugly fitted inside the bottom of each compartment or receptacle as 10 or 12 and secured there by any suitable means as by the latch member 28.

Now, to provide that the cloth cup 22 will not be bowed upwardly when the air draft is applied to it I find it desirable to super-impose upon the upper side of cup 22 a grill like retaining member 30 so that the cloth material will be held in a substantially flat plane. Another solution might be to sew the billiard cloth to a screen or grill disposed beneath the cloth so as to provide a smooth upper surface. This is a rather essential factor in the operation of my equipment in that the column of sand under the influence of the air blast should be the same entirely across the bottom of each receptacle to the end that equal resistance will be encountered and there will be no tendency for the finely divided air streams to unite and act as a jet on any portion of the sand.

Suitable means must be provided for drawing off the heavier materials at the bottom of each receptacle or compartment. This can be accomplished by venting the lower portion of the receptacle or after the showing of my present illustration, by providing a slide cut-off as 32 adapted to slide within the housing member 34 so that when the slide is forced clear in, the sand may pass entirely over it without coming in contact with cloth 22 and recoveries of the desired heavy materials can then be effected by removing the air cone 26.

Each compartment as 10, 12 etc. needs to be provided with a source of air under pressure. In my present illustration I have indicated a pressure blower 36. This I prefer to be of the so called impeller type which has the capacity of creating pressures up to 10 or 12 pounds per square inch, and at the same time being a high speed unit can handle large volumes of air. Any

suitable motive power might be supplied to blower 36 altho in keeping with the general desire to use a machine of this type for gold recovery in those localities where water is at a premium, I have indicated an air cooled internal combustion motor as 38. The blower is provided with an intake as 40 which, in certain instances, might need be screened, and a discharge pipe 42. This discharge by suitable Siamese connections can be led to any 10 desired number of receptacles or bins. In the illustrations I have shown only two bins. I wish it to be clearly understood that conditions govern the choice of the number of bins employed and there might be any reasonable number of the 15 same or in case of batch separation possibly only one might be used. Under certain conditions where the recovery of metals might be very difficult as, for instance, very fine and flaky materials it might be desirable to have several receptacles or bins disposed one below the other. Then again if a continuous operation is desirable it may be necessary to have one more bin than is essential for the required separation in that one bin can be shut off, as by slide 32, the metal 20 recoveries made, and while that operation is taking place the materials can be permitted to flow into the next lower bin.

Normally I prefer that a hopper, as 44, be provided to insure a fairly even flow of materials thru my machine and further usually find it sufficient to provide a simple control gate as 46. Under certain conditions it might be necessary to provide a mechanical feeding arrangement to insure the proper feeding of wet materials or materials which tend to pack. In some instances it may be necessary to provide screening arrangements of which there are many different types and as they form no part of my invention I have not shown the same. It is necessary however 40 that the material passing thru the machine be of more or less uniform composition inasmuch as the air pressure is quite critical and any factor which would change the rate of air passage thru the materials would necessitate manual control 45 of the air pressure. This control I have provided by placing a butterfly valve as 48 in each of the air ducts 50.

Under certain conditions it is found desirable 50 to provide a vibrating means for my equipment. In the present instance I have shown this as an eccentric weight 52 which is secured to the extension of the blower shaft as 54. This in turn is suitably journaled on bearings 56 which are secured to the main frame of the machine 58. To 55 the end of making my machine as portable as possible, I have provided the blower and its motor as a unit on a secondary frame 60 which is adapted to be secured to the main frame 58 as by brackets 62. This permits the two units to be 60 separated for transportation and ease of handling.

Method of operation

In operating my device the first bin as 10, is 65 filled with sand from hopper 44. The air is then turned on and the sand will be seen to rise in bins 10 and 12. This raising of the sand is due to the fact that the air pressure tends to float the same and we have an existing condition which is analogous to quick sand which is merely sand held 70 in suspension in water. In this state the sand has no power of packing in that the different particles do not actually touch each other but

are supported from each other by a film of air. In this condition, metal which may be present with the sand has no supporting means and as the air pressure is only sufficient to float in part the sand, the heavier metals sink to the bottom 5 of the bin. Even the finest gold particles resting on a floating grain of sand are sufficient to revolve that grain of sand and cause the metal to drop.

When the sand is aerated or floating as it were, it acts much as water and the illustration in Figure 3 is quite a truthful reproduction, in that the sand will flow from one level to the next just as so much water would do but as the sand moves from wall 18 to wall 20 it is being constantly agitated by the air stream and if desired is sifted by 15 the agitating means. The truth of the statement that the air actually supports or floats the sand is evident when the air blast is turned off as when this occurs the sand actually settles down to about two thirds of its original height proving 20 quite conclusively that the air properly adjusted will actually hold the sand in suspension. A most interesting experiment can be conducted by laying a coin on the sand when it is at rest and naturally the coin stays right on the surface due 25 to the packing of the sand particles upon one another. As soon as the air is turned on however, the coin will not stay on the surface of the sand for an instant but disappears below the surface 30 and falls to the bottom of the bin, just as tho it were placed in a vessel of water.

In stratifying different materials of substantially the same specific gravity a most peculiar phenomenon is experienced. For instance different kinds of sand whose specific gravity is very 35 nearly the same, but which differs to a degree, when placed in this machine will quickly assume a stratification corresponding to their specific gravity—the heavier materials in the bottom and the lighter materials at the top. The same is 40 true of grain. Take two grains as wheat and barley for instance. The wheat will settle quickly to the bottom whereas the barley being a lighter material will seek the upper level. It is believed, 45 it will be clear that once the materials are stratified their separation can be easily accomplished it being necessary only to vent the bins at different elevations to provide this separation.

The foregoing description and the accompanying 50 drawings are believed to clearly disclose a preferred embodiment of my invention but it will be understood that this disclosure is merely illustrative and that such changes in the invention 55 may be made as are fairly within the scope and spirit of the following claim.

I claim:

In a stepped, multi-chamber, pneumatic, dry ore separator having an elevated feed hopper, and including a separating chamber open at top 60 and bottom and having a discharge wall with its upper edge terminating below the upper edges of the remaining walls of the chamber, the combination of a hollow, removable open-top, air-distributer head inserted in the lower end of the 65 chamber, a separable cover pervious to air mounted on the open-top hollow head and forming the bottom of said chamber, a separable retaining grid forming a weight and resting on said cover, one wall of said chamber having a slot above said 70 grid for the insertion of a slide plate which is adapted to form an auxiliary chamber-bottom.

EDWIN M. RUSK.
